UNITED STATES PATENT OFFICE.

WILLIAM HENRY DRURY, OF WALTHAM, MASSACHUSETTS.

MECHANISM FOR WEAVING.

972,349.

Specification of Letters Patent. Patented Oct. 11, 1910.

Application filed July 6, 1909. Serial No. 506,438.

To all whom it may concern:

Be it known that I, WILLIAM HENRY DRURY, a citizen of the United States, residing at Waltham, in the county of Middlesex 5 and State of Massachusetts, have invented certain new and useful Mechanism for Weaving, of which the following is a specification.

The invention is an attachment to a machine for weaving textile fabrics, and causes 10 the desired shed-formation to be made for each throw of the shuttle. It is useful in all styles of weaving, but relates more especially to figured weaving, and is intended to be substituted in place of the jacquard in 15 all such work as ordinarily is done with the jacquard. It dispenses with the perforated cards, the revolving square or hexagon or octagon prism called the "cylinder," the griffs, needles, needleboard, coiled springs, 20 spring-box pins, resting rods and the other usual accompaniments of the jacquard above the bottom board next under the jacquard hooks, including the usual cumbersome mechanism for operating the griffs and the 25 cards. Substantially the same bottom board, cords, compart board, heddles and lingoës are used with the invention as with the jacquard.

The invention can do anything the jacquard can do, is useful for all purposes for 30 which the jacquard is used, and also has several useful advantages over the jacquard.

In figured weaving the principal objects 35 of the invention are the following: 1. To accomplish the minimum of wear on the warp threads and heddle cords, by providing means to keep continuously in the upper part of the shed during any desired number of consecutive picks such of the warp 40 threads as are needed up thereat, and to keep the warp threads from making any movement down or up other than what is necessitated by the style of weave for the time being, so as to simplify the work of designing for patterns, diminish breakages and 45 stoppages, improve the quality of goods produced and increase the durability of the heddle cords. 2. To accomplish increased rapidity of transformation of the shed from 50 each pick to the next, by providing means whereby instantly at the end of each pick, before it is possible to throw the shuttle, the desired shed may be formed for the next pick, so that increased production of goods

may be obtained within a given time and 55 with given expenditure of power. 3. To eliminate the noise and most of the discomforts peculiarly incidental to figured weaving as ordinarily done, and to contribute to the health and comfort of weavers by 60 affording them improved conditions of working. 4. To provide in a given bulk vastly more ample facilities for elaborateness of patterns than ordinary, by using therefor a design sheet less than 1/200 as bulky as, and 65 more durable and reliable than, the ordinary means. 5. To provide in doing figured weaving simpler means than ordinarily used, by abolishing griffs and much cumbersome and complicated mechanism in ordinary use 70 for working griffs and chains of cards, and by causing the shed-formation to be selected and made with mechanism which requires almost no power from the loom and only a single and slight connection with the 75 working machinery of the loom.

The invention by which these objects are attained consists of special mechanism to make selection of the shed-formation at each pick, special mechanism to make the 80 shed-formation in conformity to such selection, and means to make selective connection between the shed-selecting and the shed-forming mechanisms. The shed-selecting mechanism applies pneumatics to selection 85 of the shed-formation, and consists of a design sheet or design valve and perforated and unperforated spots therein appropriated to representing the original textile design which has been planned for the predetermined 90 pattern, and means to sustain and operate the design sheet in an air-tight chamber in which compressed air is maintained at desired degree of pressure. The shed-forming mechanism applies pneumatics to making 95 the shed-formation in conformity to said selection, by means of small air hoists which correspond in number and in numerical order to the spots on the design sheet appropriated to representing the original textile 100 design as before mentioned. With the neck cords of the loom harness running through the bottom board and attached to the lower ends of the piston rods of the air hoists, the warp threads are operated by the piston rods 105 in a manner resembling that in which they ordinarily are operated by jacquard hooks. Selective connection between the shed-select-

ing and the shed-forming mechanisms is made by means of small air tubes extending from the one to the other.

The invention is represented in the accompanying drawings.

Figure 1 is a vertical section of so much of the shed-selecting mechanism as consists of the design chamber, whose front is at the left of the figure, the design sheet or design 10 valve shown in a roll on a lower spool and in a smaller roll on an upper spool, the feed-rollers which move the sheet or valve along, and the tube holder across whose surface the sheet or valve slides. The figure also 15 shows at the right a view of short pieces of some of the small tubes which extend from the tube holder to the air hoists, and shows a view of some of the frame-work on the farther side of the chamber which supports 20 the mechanism for actuating the feed-rollers. Fig. 2 is a view partly in section, and partly broken away, looking from the rear of the design chamber, the parts in section being on the line 2, 2 of Fig. 1, the view inside 25 the chamber being representative of the feed-rollers and spools, and the parts outside being representative of the mechanism connecting with said rollers and spools. Fig. 3 is a side elevation of the gearing by which 30 said rollers are revolved, being another view of the gearing shown at the right in Fig. 2. Fig. 4 is a view of the mechanism on line 4, 4 of Fig. 2, looking in the direction indicated by the arrow near the top of that line, 35 and this mechanism consists of the ratchets and the pawls and cam for operating the middle gear of Fig. 3. Fig. 5 is an enlarged detail view of one of the ratchets inside said chamber seen at the left in Fig. 2, which is 40 to hold the corresponding spool from turning when the design roll is not fastened to it, and this Fig. 5 shows how the shaft of the spool is held and how it may be removed. Fig. 6 is an enlarged horizontal section on 45 line 6, 6 of Fig. 1, looking down as indicated by the arrow pointing to that line. This view is partly broken away, and shows part of the design roll, part of the spool and its shaft, another view of the ratchet last mentioned 50 and part of the spiral spring which holds taut the design sheet or roll. Fig. 7 is a side elevation of the chamber which holds the cylinders of the air hoists, two of which are shown in full length where the 55 side of the chamber is broken away. This figure shows portions of the small tubes which extend from said tube holder. The mechanism shown above the chamber is for adjusting the openness of the shed by limiting the height to which the upper ends of 60 the piston rods of the air hoists can rise. Fig. 8 is a horizontal section, looking downward, of four rows of the air hoists. The two top rows are on the line 8^a, 8^a of Fig. 7, 65 and the two lower rows are on line 8, 8

thereof. The dotted lines indicate the part of the chamber to which the bottom plate of the chamber is fastened. This figure also shows how the said small tubes connect with the air hoists. Fig. 9 is a view on the line 70 9, 9 of Fig. 2, looking in the direction pointed to by the arrow near that line. This shows the spiral springs for keeping the design roll tight on the spools. Fig. 10 is an enlarged longitudinal section of one of the 75 air hoists. Fig. 11 is a view, partly in section, of a modification. Fig. 12 is a longitudinal section of another modification. Fig. 13 is a cross section on line 13, 13 of Fig. 10. Fig. 14 is a cross section on line 80 14, 14 of Fig. 12. Fig. 15 is a cross section on line 15, 15 of Fig. 10. Fig. 16 is a cross section on line 16, 16 of Fig. 10. Fig. 17 is a cross section on line 17, 17 of Fig. 12. Fig. 18 is a cross section on line 18, 18 of 85 Fig. 10. Fig. 19 is a cross section on line 19, 19 of Fig. 11. Fig. 20 represents a small piece of ordinary design paper ruled into squares, with an 8-harness sateen weave designed thereon as indicated by crosses, and 90 the word "It" designed for the figure as indicated by small circles. This represents an original textile design. Fig. 21 represents a small piece of the design roll or design valve with the first upper 19 cross lines 95 of said original design transferred thereto on the principle to be stated. Fig. 22 is a front elevation of the tube holder within the design chamber, the small idlers for holding the design roll against the feed- 100 rollers, the guides for guiding an end of the design roll from one spool to the other, and means for holding some of the parts. Portions are broken away. This shows the surface across which the design roll slides, and 105 four horizontal rows of small circular orifices into the small tubes before mentioned. These orifices are either opened by the perforations or closed by the unperforated spots in the design roll, either to admit or to exclude the entrance of air through the orifices. 110

Ordinary design paper sometimes is ruled into oblongs but oftener into squares. Each crosswise row of squares on the original textile design drawn on such paper represents 115 a pick of the weaving and indicates where warp threads and weft threads respectively shall appear on the surface of the corresponding fabric at that pick. Ordinarily in figured weaving each crosswise row of 120 the original design is transferred to a pasteboard card in which the warp squares of the design are represented by perforations and the weft ones by unperforated spots. Such cards are prepared in accordance with the 125 entire design and laced together into an endless chain in the order of the crosswise rows of the design, and such chain of cards is connected with the warp threads through needles and hooks of jacquard mechanism in 130

such manner and corresponding order of arrangement that by the joint action of the cards, needles, hooks and other weaving mechanism a pattern in conformity to the 5 design is produced in the fabric manufactured. Likewise in the present instance the crosswise rows of the original design *b*, of which Fig. 20 is an illustration, are transferred consecutively to corresponding 10 successive lengthwise divisions or sections of design roll *a* (Figs. 1, 6, 21) on the same principle as that on which they ordinarily are transferred to cards in jacquard weaving. The warp squares of the original 15 design are represented by perforations, and the weft ones by unperforated spots, in the design roll, and the entire design is represented by the design roll in the sense in which it is ordinarily represented by a chain 20 of cards. Also the design roll is connected with the warp threads through air tubes and air hoists in such manner and corresponding order of arrangement that by the joint action of the design roll, air tubes, air 25 hoists and other weaving mechanism a pattern in conformity to the original design is produced in the fabric manufactured. Said design roll *a* is preferably of draftsman's tracing cloth, or may be of some tough and 30 strong quality of paper comparatively exempt from influence of ordinary climatic changes, or may be of very thin sheet metal or any suitable flexible material. The circles *a*¹ (Fig. 21) represent peg holes along 35 the border of the design roll. Like peg holes are to be along the opposite border of the same. They are usually 1/2 inch apart between centers, and are used for feeding the roll by the pegs *a*² (Fig. 1) in the feed- 40 rollers *a*³.

If a fabric is to be woven with the design sheet in Fig. 21, and with white warp and black weft, and if the designed word is to read "It" in black on the face of the fabric, 45 the fabric must be woven face down; for the word will read "Ti" in white on the upper surface of the fabric. But if the fabric is woven with the design sheet turned around border for border and surface for surface, 50 the word will read "It" in white on the upper surface.

It is recommended that a design roll of full length be about 4 inches diameter and on a one-inch spool. Such roll will be 300 feet 55 long. Usually 1/2 inch of the length of the design roll is appropriated to representing a crosswise row of the original design, so that such a roll as mentioned is equivalent to 7200 cards; and it is 1/5 the minimum length 60 and less than 1/200 the bulk of an ordinary chain of cards of that capacity. As provision is made for readily taking out and putting in a roll, it is obvious that a single design of great elaborateness may be on 65 several rolls which may be worked in suc-

cession conveniently. Hence there is facility for producing a woven pattern of extraordinary elaborateness conveniently.

The orifices *a*⁴ (Figs. 1, 22) of the tube holder *a*⁵ must correspond in number and 70 numerical order to the spots on a division of the design roll which are appropriated to representing a crosswise row of the original design, and must be the same distance apart both ways and of the same diameter as the 75 spots, so that the orifices will be in alinement with the corresponding spots at each resting stage of the advance of the design roll. The front surface of the tube holder *a*⁵ should be smooth, so that the design roll will slide 80 across it without noise, violence or appreciable wear, and be durable and reliable.

The design chamber *a*⁶ is to be air-tight, and care is to be taken to prevent leakage therefrom except through the perforations 85 in the design roll into the corresponding orifices *a*⁴ and small tubes *a*⁹. The front *a*⁷ is to be removable readily, for convenience in taking out or putting in a design roll. Thin rubber packing is usually provided be- 90 tween the front plate *a*⁷ and the front edges of the shell of the design chamber, and the front is usually clamped to the chamber by a suitable number of clamping buttons (not shown) in well known manner, so that it 95 can be removed handily by slight turn of the buttons. A glass window *a*⁸ in the front *a*⁷ is to enable the weaver to see inside. The chamber is intended to be stationed lengthwise of the loom at any height preferred, 100 and may, if desired, be on level with the weaver's head, so that he can see or do anything inside while standing on the floor. Compressed air is to be maintained within 105 the chamber at desired degree of pressure, and may be admitted at any place preferred. In the present instance it is admitted through the tube *a*¹⁰. Usually pains is taken to provide pure air, and it is conveyed to the design chamber through an air hose 110 from a suitable reservoir outside or inside the weaving room. The pressure is maintained in the reservoir by a compressor at higher degree than is needed in the design chamber, and the pressure in the chamber is 115 regulated by an ordinary reducing valve at any convenient place between the reservoir and the chamber. A single reservoir of sufficient capacity may supply air for any desired number of looms. Supply of air to 120 the chamber may be shut off or let on readily by a cock or valve in the air hose (not shown) at a place near the chamber, in the way common in using compressed air under analogous circumstances.

The view shown in Fig. 4 is behind the framework *a*¹¹ in Fig. 1, and is as if seen by a person looking from the hither side of Fig. 1, imagining the intervening things which obstruct the view to be out of sight. 130

The cam c is fixed to the shaft of wheel c^1 (Fig. 2) by which alone the invention is connected with the driving machinery of the accompanying loom. The purpose of such connection is to work cam c in unison with the shuttle of the loom so as to advance design sheet a intermittently, one division at each step, which is usually $1/2$ inch. Each step of such advance is to be immediately at the end of each throw of the shuttle, and the movement of the cam c must be timed accordingly. Wheel c^1 may be driven from the shaft which usually works the griff frame of a jacquard up and down, or it may be driven from any other shaft of the loom which will insure the unison of movement desired. The cam roller c^2 , which travels in the heart-shaped cam slot c^3 , revolves on a pin fixed to the slide c^4 which carries the pawls c^5 and c^6 of the ratchets c^7 and c^8 . These ratchets are fixed to the shaft c^9 of gear c^{10} (Figs. 3, 4), which drives gears c^{11} fixed to the shafts of feed rollers a^3 . As cam c revolves from the position shown, with cam roller c^2 nearest the center of the cam, pawl c^5 is carried in almost an instant to the right far enough to move ratchet c^7 the distance of two teeth, causing gears c^{10} and c^{11} to rotate two teeth, and advance feed rollers a^3 one peg so as to slide design sheet a upward across the surface of tube holder a^5 the distance of one division. The cam roller is in the relatively long circular part of the cam slot during most of the revolution of the cam, so that the pawl is stationary during that time. In a relatively minute part of such revolution the pawl is made to jump back to its original place and then push the ratchet forward two teeth more, and so on. The lever-acting parts c^{13} and c^{14} which hold the pins on which c^5 and c^6 swing, are linked together by link c^{12} and move unitedly. Lever c^{13} bears on its upper end a pin which can be inserted at will in either of two holes in the holder c^{16} which is rigidly fixed to the slide c^4 . The pin is now in the right-hand hole. By moving the end of lever c^{13} to the left and inserting the pin in hole c^{15} pawl c^5 is made inoperative, and pawl c^6 is made operative to work on ratchet c^8 , in which instance the movements of gears c^{10} and c^{11} and of feed rollers a^3 and design sheet a are the reverse of what they were before. Thus it is seen that pawl c^5 operates when pawl c^6 does not, and vice versa; and when one goes into operative position the other goes out thereof. The provision here noted is made because occasionally it is necessary to unweave an imperfect place in the fabric which is in process of weaving, and because also often it is desirable to work the design sheet forward and upward from beginning to end and then backward and downward from end to beginning, so as to produce a

symmetrical figure composed of two parts which are the reverse of each other with a common center.

The design sheet a must be rolled up by one spool as fast as it is unrolled from the other. This may be done with two trains of clock work, one acting on one spool and the other on the other; both normally tending to roll up the sheet, and one train unwinding while the other train is winding up. Another device working on that principle is shown in the drawings, being two spiral springs d and d^1 , as seen in Fig. 9. Each tends to roll up the sheet. Unrolling the sheet has the effect of winding up the spring which acts on the spool from which the sheet is unrolled, and the other spring unwinds while it is rolling up the sheet. After advancing forward and upward until the lower spring has been wound up and the upper one has unwound, the sheet may be advanced backward and downward until the upper spring has been wound up and the lower one has unwound. The device is useful in weaving short patterns. Either spring may be wound up or unwound by turning the nearest worm d^2 .

The shafts d^3 of spools d^4 are square in cross section, except their round bearings at the left-hand ends, which are at the right of Fig. 2, as this view is from the rear of design chamber a^6 (Fig. 1). The right-hand ends pass through the flanges d^5 , and are held by the jaws d^6 (Fig. 5) in the square channels of the blocks d^7 , which join the flanges to the ratchets d^8 . These ratchets are fixed to the short shafts d^9 , as also are the sleeves d^{10} which hold the inner ends of the springs d and d^1 whose outer ends are held on the rims d^{11} fixed to the worm gears d^{12} which are not fixedly attached to said sleeves otherwise than by the inner ends of said springs. The short shafts d^9 have their journals in the right-hand side plate d^{13} of the design chamber. It is apparent at sight how the jaws d^6 open, shut and act. Each ratchet d^8 is provided with a pawl d^{14} which is put into engagement with the ratchet to prevent said springs from unwinding when the design sheet is removed from the design chamber.

No special means of rolling up the design sheet as it unrolls is claimed as part of the invention, and any means suitable to accomplish the desired result may be used.

The small cylinders h (Fig. 7) of the air hoists are sustained and mainly contained in a single oblong air-tight cylinder chamber h^1 , whose front is at the left of Fig. 7 which is an elevation of the right-hand side. This chamber is intended to be stationed above the loom with its right-hand side over the right-hand side of the loom, in the place ordinarily occupied by a jacquard. Compressed air is to be maintained in this cham-

ber at desired degree of pressure, and may be supplied from the same reservoir as said design chamber. The air may be admitted at any place preferred, but the place provided here is through the pipe h^2 . The pressure is regulated, and the supply let on or shut off, in the same way as in the design chamber. If preferred, the two chambers may be connected with each other by a tube between them, and in that case a single air hose from the reservoir to either of the chambers may supply the two. A separate air hoist is provided for each warp thread, unless the woven pattern is to be repeated crosswise of the fabric, in which latter case each piston rod can operate as many warp threads as a hook can in jacquard weaving. Each cylinder h has two openings h^3 and h^4 from within the chamber, one above and one below the piston of the air hoist, and has two exhaust openings h^5 and h^6 outside the chamber, one below and one above the piston. Each cylinder h is accompanied by a compound valve, which is compounded of four valves h^7 , h^8 , h^9 , and h^{10} , which are so connected with each other that all of them move up or down together. Two of them, h^7 and h^8 , work inside, and two, h^9 and h^{10} , outside the chamber. One of them, h^7 , opens and closes the lower entrance opening, another, h^8 , opens and closes the upper entrance, another, h^9 , the lower exhaust opening, and another, h^{10} , the upper one. The lower exhaust and entrance valves h^7 and h^8 are immediately connected with each other by a rod h^{11} which passes through the bottom plate of the cylinder chamber, and the lower end of this rod works as a piston in a small piston chamber h^{12} to which one of the small tubes a^9 extends from the design chamber. The upper entrance and exhaust valves are immediately connected with each other by a rod h^{13} which passes through the top plate of the cylinder chamber, and this rod may be an extension of rod h^{11} or not, as preferred, so long as the two are connected with each other and move together. In the present instance the part of the cylinder inside the chamber is surrounded nearly the whole length by a sleeve, and a short piece of each end of the sleeve is one of the four valves mentioned. The sleeve and the two rods h^{11} and h^{13} connect the four valves together. Rod h^{13} is of less diameter than rod h^{11} , so that when pressure ceases from within the corresponding small tube a^9 , the pressure within the large chamber will force the four valves down to their lowermost positions. Thus, if rod h^{11} is 1/8 inch and rod h^{13} is 3/32 inch diameter, with the same pressure per square inch on both, the upward pressure on the lower end of rod h^{11} will be to the downward pressure thereon (which is equal to the excess thereof above the upward pressure on the lower end of rod h^{13}) as 16 to 7. The excess represented by 9 will force the four valves up; and when pressure within the small piston chamber h^{12} is suspended, the net downward pressure represented by 7 added to the weight of the valves and rods will force the valves down. When the valves are forced up the effect is to close the lower exhaust h^5 , open the upper exhaust h^6 , open the lower entrance h^4 , and close the upper entrance h^3 . Thereupon compressed air rushes into entrance h^4 under the piston h^{14} , and the corresponding piston rod, warp thread and lingo are forced to rise. But when the valves are forced to drop the effect is to close the upper exhaust, open the lower one, open the upper entrance and close the lower one. Thereupon compressed air rushes into the upper entrance above the piston, and the piston rod is forced to descend by the combined action of the weight of the piston rod and corresponding lingo, the tension of the corresponding warp thread and the pressure of compressed air above the piston. The long piston rod bears an upper stop h^{17} and a lower one h^{18} , to limit the utmost upward and the regular downward stroke of the piston.

Fig. 8 shows how the air hoists are arranged in the cylinder chamber, whose front is at the left. The upper row is treated as being numbered consecutively 1 to 16 from left to right, the next lower row 17 to 32 from left to right, and so on. There would be 26 such rows in a machine for 416 warp threads. The small tubes a^9 coming from the design chamber are connected with the air hoists in the order of their numbers. Thus, tube 1 connects with air hoist 1, tube 2 with air hoist 2, and so on. The warp threads also are treated as being numbered consecutively from left to right facing the front of the loom.

From what has been said hereinbefore it is seen that there are six systems of units, namely, the system of squares on a crosswise row of the original design, the system of spots on each division of the design sheet, the system of orifices in the tube holder, the system of small tubes extending from the orifices, the system of air hoists, and the system of warp threads. Each system is seen to be only a multiplication of units, and the systems are treated as being numbered correspondingly, each to the others, so that any unit in one system has a corresponding unit of the same number in each of the other systems.

The long piston rod of each air hoist extends through both ends of the cylinder. The upper end h^{15} of the rod is of larger diameter than the lower end h^{16} , so that the downward pressure of air on the piston h^{14} is less than the upward, as it should be. The upper ends are larger also because these are used in adjusting the openness of the

shed of the warp threads by limiting the height to which the rods can rise, and their larger diameter renders them sufficiently strong and stiff to endure this use without bending or springing. The mechanism for the adjusting is shown in Fig. 7. The horizontal board or plate m which the rods encounter is moved up or down by turning the wheel m^1 , whose shaft drives the bevel gears shown, by which the right-hand screw m^2 and the left-hand screw m^3 , with which the board is connected by nuts, are turned oppositely to each other. The under side of the board is to be covered with sheet rubber, or the like. When the piston rods rise their upper ends encounter the stopping board which limits their rise. The board shown is level. An inclined one with level stopping strips from side to side on its under surface, and with the rear nut higher than the front one, can be used instead of the level board, so that its rear will be higher than its front, and in this way all the warp threads in the upper part of the shed can be kept on about the same incline, so that the heddles near the reed will not need to be raised so high as those more remote. Obviously a stopping board can be used which will limit the height of raising the heddles relatively to each other to suit any requirement in respect thereto.

Referring again to the shed-selecting mechanism, it is seen that in reality the design sheet is a valve which opens and shuts the entrances to the small tubes which control the compound valves of the air hoists. At the end of each pick the perforations, by letting on or keeping on the upward pressure in the air hoists, cause the corresponding warp threads to be hoisted or else to be kept hoisted for the next pick. The purpose of the almost instantaneous transition from each step of advance to the next is to make sure that during the transition there will be practically no interruption of pressure in a small tube whose orifice is open at the beginning of the transition, and that if a perforation shall be over that orifice at the end of the transition, the corresponding compound valve will stay up and cause the corresponding air-hoist piston rod to continue holding up its warp thread. But if at the end of the transition an unperforated spot shall succeed to a perforation and close that orifice, the corresponding compound valve will drop and the corresponding piston rod and warp thread will descend. Also if at the end of the transition a perforation shall succeed to an unperforated spot, the corresponding compound valve will rise instantly and cause the corresponding piston rod and warp thread to rise. It frequently happens in figured weaving that a certain warp thread will be needed up at several consecutive picks, and this will occur to many other

warp threads. This is illustrated in Fig. 21 in case of so few as 32 warp threads. Of the 32 there are 20 up at the first pick. At the 2nd pick 17 of the same threads are needed up. At the 3rd pick 14 are needed up that were up at the 2nd. At the 4th pick 7 are needed up that were up at the 3rd. And taking the case of a single thread, the 13th is up at 7 consecutive picks, then down at the 8th, and then up again at 7 in succession. The like is very common in figured weaving. In the present invention the design sheet automatically causes all threads in the upper part of the shed at one pick that are needed up at the next pick to remain up. It causes to be lowered only the threads not needed up at the next pick, and simultaneously with the lowering of those it causes to be hoisted such additional threads, if any, as are needed up at the next pick to accompany those remaining up. Thus a rapid transformation of the shed from pick to pick is going on, and some of the lower and some of the upper threads are constantly shifting or interchanging their positions from down to up and from up to down, and finding their appropriate places in conformity to the selection of the design sheet, while the remaining ones stay down or up, as the case may be, until their turns come to shift or interchange their positions appropriately. Consequently there is the least possible loss of time in getting ready for each pick, and there is the minimum of wear on the warp threads and heddle cords due to chafing. No exhausts are in the small tubes a^9 , for the valve rod h^{11} working in any small piston chamber h^{12} is not so tight as to make a special exhaust necessary, and it is found that as soon as an unperforated spot of design sheet a succeeds to a perforation over the corresponding orifice in the tube holder a^5 the corresponding compound valve of an air hoist drops, without need of a special exhaust.

Fig. 12 shows a modification of the air hoist, which can be used if the chamber h^1 is converted into a vacuum chamber, causing the atmosphere to act like compressed air. The exits will then be inside the vacuum chamber, and the entrances outside. When the valve rod h^{11} is forced upward the effect is to open the outside lower entrance o , close the exit o^1 , open the exit o^2 , and close the entrance o^3 , with the result that atmospheric pressure will force the piston h^{14} up. In this case the valve rod h^{13} will be larger than h^{11} , so that on suspense of pressure in chamber h^{12} atmospheric pressure on the upper rod h^{13} will force the compound valve down, and the result will be that piston h^{14} will be forced down by atmospheric pressure above it, and the piston itself will close the exit o^1 .

Fig. 11 shows another modification which

can be used with a vacuum chamber. Compressed air from the design chamber through the small tube a^9 will force h^{11} up and rush into entrance n and force the piston up, thus 5 combining compressed air below the piston with a vacuum above it. In other respects the construction and action are the same as with the modification in Fig. 12.

The applicant desires to include in the 10 claims the utilization of a vacuum in operating the warp threads.

Some of the measurements recommended are 1/16 inch inside diameter for the small tubes, 5/16 inch outside and 1/4 inch inside 15 diameter for the cylinders placed 5/8 inch apart between centers from front to rear and 1/2 inch from side to side, 11 inches front to rear, 15 inches side to side and 6 and 3/8 inches high for outside dimensions 20 of cylinder chamber suitable for 4/16 air hoists, 1/8 inch diameter for the lower valve rod and 5/64 inch for the upper one, 1/8 inch diameter for upper part of piston rod and 5/64 inch for lower part, and 4 and 25 1/2 inches for full stroke of piston.

The following claims are made:

1. In apparatus for weaving, the combination with heddles and harness to hold the warp threads of the fabric to be woven, and 30 a plurality of hoists to work the harness

and make the selected shed formation of the warp threads, and means to operate the hoists, of a perforated design sheet representing the design of the fabric, a valve seat across whose surface said sheet may slide 35 and orifices in said seat, means to sustain said parts, means to slide said sheet across said surface so as to bring perforations in desired successive portions of said sheet into alignment with corresponding orifices at desired intervals, tubes to make connection between said orifices and the means to operate said hoists, and means to exert pneumatic pressure through the perforations and corresponding orifices and tubes, all coöperating 40 to select and make the shed formation, substantially as set forth.

2. In apparatus for weaving, the combination of heddles and harness to hold the warp threads of the fabric to be woven, a 50 plurality of air hoists to work the harness and make the selected shed formation of the warp threads, and means to operate the air hoists, including means to select the shed formation, substantially as set forth.

WILLIAM HENRY DRURY.
